UNITED STATES PATENT OFFICE.

BURTON W. SWEET AND FRANKLIN SCHNEIDER, OF CLEVELAND, OHIO, ASSIGNEES TO
THE VAN DORN ELECTRIC TOOL COMPANY, OF CLEVELAND, OHIO, A CORPORATION
OF OHIO:

ELECTROMAGNETIC SWITCH.

1,238,719.

Specification of Letters Patent. Patented Aug. 28, 1917.

Application filed August 30, 1911. Serial No. 846,898.

To all whom it may concern:

Be it known that we, BURTON W. SWEET and FRANKLIN SCHNEIDER, citizens of the United States, residing at Cleveland, in the 5 county of Cuyahoga and State of Ohio, have invented certain new and useful Improvements in Electromagnetic Switches, of which the following is a specification.

Our invention relates to improvements in 10 electro-magnetic switches, and has for its object, the provision of switching mechanism that is simple and effective in its operation and adapted automatically to open the circuit to the connected apparatus to 15 avoid accidents, in case the exciting current is interrupted.

Our said invention is primarily adapted for employment in connection with electrically operated drills, reamers and the 20 like, and the construction is designed for the control of relatively heavy currents by the operator and at a distance from the drill or other device. The energizing circuit is initially closed by the operative at 25 a manually closed switch, while the circuit is completed to the drill or other mechanism, by electro-magnetic means thereby called into operation. The drill is thus maintained under this indirect manual control, but in the event that the current supply fails from any cause, our improved 30 apparatus provides electro-magnetic means for automatically disconnecting said drill or other connected appliance.

The foregoing, together with additional 35 advantages and details of our preferred construction, will be more fully explained in connection with the accompanying drawings, wherein:

Figures I. and II., are views in elevation 40 of the switch mechanism with the circuit-closing contacts respectively separated and closed.

Fig. III. is a cross-sectional view showing 45 the releasing device or trip.

Fig. IV. is a vertical sectional view 50 through the switch.

Fig. V. is a detail, partly broken away, 55 showing one of the renewable carbon contacts and spring.

Fig. VI. is a similar view of the electro-magnetically actuated controlling switch, and

Fig. VII. is a diagram of the controlling 55 and energizing circuits.

Throughout the several figures of the drawings, we have employed the same character of reference to indicate similar parts, or the diagrammatic representation of such parts.

60

Referring first to the structural figures of the drawings, we may explain the features thereof as herein embodied, and thereafter set forth the utility and operation of said switch mechanism in connection with 65 suitable associated apparatus and circuits.

Two solenoids *a* and *b*, are provided in the lower portion of the device, which respectively serve as circuit-closing and release magnets. The core *b'* of the magnet 70 *b* is adapted to engage the beveled end of the latch *c*, when said magnet or solenoid is excited to elevate the core (as indicated by dotted lines Fig. I.), and thereby restore the switch parts to their open-circuit position.

The core *a'* of the solenoid or magnet *a* is provided with a shoulder *a''* adapted to be engaged and retained in its elevated position, by the spring-actuated latch *c*. An 80 insulating disk at the upper extremity of core *a'* carries the movable contacts of the primary switch. This disk *d*, and the contacts *d', d'', e', e''*, which are electrically connected two by two, will close circuit with 85 corresponding spring-actuated contacts *f', f'', g', g''*, mounted upon an insulating block *f*, provided in the upper portion of the switch frame *g*. A plunger-part *e* is simultaneously actuated to operate an automatic secondary switch *h* mounted above 90 the insulating plate or block *f*.

The details of the carbon contacts (one of which is shown in Fig. V.) and of the secondary switch (shown in Fig. VI.) may well 95 be explained by referring to said fragmentary figures. Each of the stationary contacts is provided with a renewable carbon contact-member *i* retained by a transverse pin *j* within its sleeve *i'*, while a 100 coiled spring *j* affords sufficient resilient movement to insure the establishment of ample electrical contact between the opposing contact-faces.

Plunger part *e* is so positioned as to actuate the secondary switch *h* to alter its circuit whenever the circuit is opened or closed by the primary switch. Thus whenever circuit is closed by the latter, the plunger *e* is elevated to engage switch spring *k* with its 110

upper contact k'' , and when the releasing magnet b is energized to actuate the latch or trip c , the plunger e drops with disk d and its contacts, thereby permitting spring 5 k to close upon its normal resting contact k' .

Bearing the foregoing structural features in mind, we may now explain the functions and principal utility that we have in mind for our improved switch-mechanism, by 10 making reference to the diagram of Fig. VII. Therein the outer or energizing circuit terminals are indicated by A, B, and the drill motor is shown diagrammatically at M, which it is desired to operate by means 15 of our improved apparatus and circuit. A manual push-button switch S is provided for actuating or controlling the apparatus through a suitable cable indicated by the conducting-wires upon the left of the diagram. These conductors or insulated cable wires 1, 2, 3, 4 and 5 are shown on the diagram by figures upon their respective terminals for greater convenience in tracing the circuit, while certain parts of the switch 20 mechanism already explained, are indicated diagrammatically and by their appropriate character of reference.

In order to start the drill motor, the operative has simply to depress the push-button p of switch S, thereby engaging the lower contact p' thereof to close circuit through the switch S while it is desired to operate the motor. Circuit may be traced from terminal A, through conductor 3, contact p' of switch S through the solenoid a of the actuating magnet and contact k' of the secondary switch to the terminal B of the energizing circuit.

This excites solenoid a , which immediately 40 elevates its core, together with disk d and its contacts, so that the latter are engaged with the opposing stationary contacts, between which circuit is established and broken. Simultaneously the secondary 45 switch is actuated to cut out of circuit the solenoid a at k' , and close contact between k and k'' , which permits the subsequent energization of the solenoid b connected in conductor 2.

In the diagram the disk d is indicated by 50 dotted lines which inclose the contacts d' d'' and e' and e'' , electrically connected as shown. These contacts will be actuated into engagement with the stationary contact f' f'' , and g' and g'' , thereby establishing circuit from the terminals A, B, directly 55 through the primary switch contacts which are now closed, and associated conductors 4, 5, to the drill motor M. This is the running 60 position for the motor and the foregoing conditions obtain while said motor is being driven.

Whenever push-button p is released, its upper contact will be normally engaged by 65 means of a spring, and current will be auto-

matically cut off from the drill motor. On the other hand, should the current be interrupted from any cause, and said button is afterward released by the operative, the drill motor will be automatically disconnected, 70 immediately the current flows; this being effected by the release-solenoid b . Circuit may be traced under either of the conditions assumed, from terminal A, through the conductor 3 in shunt with motor M, through 75 contact p'' , conductor 2, solenoid b , and contact k'' of the secondary switch, to terminal B. This, as initially explained, will effect the separation of the primary switch contacts supplying current to the 80 motor, and change the secondary switch, to connect the actuating magnet a again in circuit.

From the foregoing, it will now be understood that the switch mechanism may with 85 advantage, be positioned at a distance from the drill motor, which, however, is maintained under the immediate control of the operative, by means of his push button switch. This switch, it will also be observed, 90 serves for the initial closure of the circuit, which is thereafter closed to the motor in shunt relation, between the primary switch contacts. The latter contacts, however, are 95 those between which the energizing circuit is broken, and for these contacts we preferably provide renewable carbon contact-parts. These features are of importance in controlling the currents of high voltage, which almost necessarily are employed.

Again, by providing the automatic release-magnet, connected in circuit as above set forth, our improved switch mechanism renders it absolutely impossible for the current to fail and thereafter reach the motor, because the motor circuit must be opened immediately through the agency of the release-magnet. Said motor, therefore, must invariably be started by the operative who has control of the push-button switch.

Having now described the preferred embodiment of our invention, together with the use to which we have applied it, and the advantages developed in such practice of our invention, we claim as new, and desire to secure by Letters Patent, together with such modifications as may be made by mere skill, the following:—

1. In an electro-magnetic switch, the combination with a reciprocated insulating 120 member, of contacts mounted thereon, co-acting contacts adapted to be engaged by the latter, a solenoid and its core connected for reciprocating said insulating member, a spring-actuated latch adapted normally to 125 lock said contacts and mounting in their position of engagement, a second solenoid adapted when energized to release said latch, an automatic switch controlled by the first mentioned solenoid adapted alternatively to 130

connect one or the other of said solenoids in the controlling circuit, and a member positioned intermediately of the reciprocated part and said automatic switch adapted to effect the concurrent actuation and locking of the latter, substantially as set forth.

2. In an automatic electro-magnetic switch, the combination with stationary and movable contacts governing the controlled circuit, of a solenoid and its core connected for the actuation of said movable contacts, a second solenoid and its core, positioned adjacent to and substantially parallel with the first solenoid, a spring-actuated latch pivoted to move at right angles to the axes of said solenoids and positioned for actuation by the core of the second solenoid; said latch being adapted automatically to lock the contacts in their position of engagement, an automatic switch controlled by the first mentioned solenoid, adapted simultaneously to connect the second solenoid in the controlling circuit upon the closure of the aforesaid contacts, and means also controlled by the latch for temporarily locking said switch in circuit with the second solenoid, substantially as set forth.

3. In an electrically actuated switch of the class described, the combination with two solenoids positioned side by side, of a switching-member connected for actuation

by the core of one of said solenoids, a latch associated with said electro-magnets and pivoted to move in a plane at right angles to their axes in position to lock the switching-member in its closed relation, and a releasing-part presenting an inclined face actuated by the core of the second solenoid to release the latch, substantially as set forth.

4. In electro-magnetic switching apparatus, the combination with switch contacts adapted to control a local circuit, of a circuit-closing electro-magnet operatively associated with said contacts, a circuit-opening electro-magnet, means controlled by said second electro-magnet for normally maintaining said contacts in their closed relation, an automatic circuit-changer operatively associated with said electro-magnets, and a manually operated circuit-closing member biased to close the circuit to the switch-opening electro-magnet and controlling the circuit to the first electro-magnet, substantially as set forth.

In testimony whereof we now affix our signatures in the presence of two witnesses.

BURTON W. SWEET.
FRANKLIN SCHNEIDER.
